UNITED STATES PATENT OFFICE.

RUDOLPH CONRADER, OF ERIE, PENNSYLVANIA.

RELIEF DEVICE AND ATTACHMENT FOR COMPRESSORS.

No. 823,845.

Specification of Letters Patent.

Patented June 19, 1906.

Application filed January 29, 1902. Serial No. 91,783.

To all whom it may concern:

Be it known that I, RUDOLPH CONRADER, a citizen of the United States, residing at Erie, in the county of Erie and State of Pennsylvania, have invented certain new and useful Improvements in Relief Devices and Attachments for Compressors; and I do hereby declare the following to be a full, clear, and exact description of the invention, such as will 10 enable others skilled in the art to which it appertains to make and use the same.

This invention relates to relief devices and attachments for compressors; and it consists in certain improvements in the construction 15 thereof, as will be hereinafter fully described, and pointed out in the claims.

The ordinary purposes of relief devices are well understood.

The object of this invention is to provide a 20 simple and effective device of this character.

Where relief devices are so designed as to produce a reduction of pressure at the compressor during the time that the relief device is in operation, it becomes necessary to provide some valve mechanism to prevent a 25 backflow of fluid from the receiver. This is ordinarily accomplished by the use of a check-valve. Where the ordinary check-valve is used, it operates with each pulsation 30 of the compressor, causing an unnecessary wear on the valve, as well as considerable noise. I have provided an attachment for the relief device which prevents this action, and this attachment is one of the features of 35 my invention.

The invention is illustrated in the accompanying drawings as follows:

Figure 1 shows a central section of the compressor and relief device on line 1 1 in Fig. 2. 40 Fig. 2 is a plan view of the compressor and relief device. Fig. 3 is an end elevation of the same viewed from the right of Fig. 2. Fig. 4 is a section of a detail of the check-valve-operating mechanism on the line 4 4 in Fig. 5. 45 Fig. 5 is a side elevation of the same detail. Fig. 6 is a central section of an alternative construction on the line 6 6 in Fig. 7. Fig. 7 is a plan view of the same construction.

A marks the compressor-cylinder, and B 50 marks the piston or plunger therein; C, the intake-valves; D, the outlet-valves. These are similar in construction to those now in common use. The valves D are of cylindrical shape and fit in the valve-chambers a, forming plungers in said chambers. The springs d are tensioned against the valves and tend to

keep them closed. A passage A' connects the outlet-ports a' a'. The outlet-passage E connects with the passage A'. Arranged in this passage is a check-valve F. The passage E connects with the pipe E', which may be called for the purpose of explaining the invention the "receiver" or "receiver connection." Each of the valve-chambers a is connected by the pipe d' with a chamber G. The chamber G is connected with the passage E by the passage g. The passage g is controlled by the valve G'. The valve G' is normally open, so that the fluid under pressure passes through the chamber G and pipes d' to the chambers a. The chambers a are normally in communication with the passage A'.

The valves D operate in the ordinary manner of pump-valves. When the relief device operates, the valve G' is closed and the pipes d' open to the atmosphere. The pressure in the chamber a therefore immediately falls below that in the passage A', so that the valves D are forced open by pressure in the cylinder A and held open by the pressure in the passage A'. As the compressor continues to operate the fluid is simply moved from end to end of the cylinder through the passage A' and ports a'.

The relief mechanism is as follows: A 85 passage g' extends from the chamber G to the atmosphere. The valve H is arranged to close this passage. The upper end of this valve is connected with the plunger H', which operates in a cylinder I. The stem of the 90 valve H passes through the gland i. A stem h extends upwardly from the plunger H'. Arranged on the top of this stem is a yoke h². This is secured in place by the nut h³. Extending from each side of the cylinder I are 95 the lugs i'. The springs H⁴ are tensioned between the yoke h² and the lugs i'. The pressure of these springs is exerted to force the valve H to its closed position. Connecting with the cylinder I is a chamber I', from 100 which is a contracted exhaust-opening i" and into which leads a passage i'. The passage i' communicates with the cylinder J, in which is arranged a plunger K. Arranged in the end of the plunger K is a valve k. This valve 105 is arranged to seat over the passage i' and close it. Leading into the cylinder J is a connection for the receiver J'. A pipe l leads from this connection to the receiver connection E', so that the cylinder J has receiver-pressure at all times. Extending outwardly from the plunger J is a pin k'. This operates 110

against a lever L. The lever L is pivoted at j on an arm j. The arm j extends from the cylinder J. A lug j² extends from the bottom of the cylinder J. A spring M is tensioned between this lug and the end of the lever L, the connection on the lever L being formed by the tension-bolt n and the nut m'. An arm l extends from the upper end of the lever L and is provided with the set-screw l', by which the movement of the lever L may be limited. Extending from the lever L also is an arm N, on which is placed the weight N'. The weight may be shifted on the arm N and secured in any position by means of the screw n. Extending from the yoke h² is an arm h'. In the end of this arm is a hollow screw g⁴, arranged to be locked in any adjusted position by means of the jam-nut g⁵. The stem g' of the valve G' extends into the screw g⁴. A spring g' is arranged to move the valve G' to its seat.

The operation of the several mechanisms is as follows: When the receiver-pressure rises above the desired maximum, it forces the plunger K outwardly, thus opening the valve k. Air or fluid under pressure passes through the passage i² and operating on the under side of the plunger H' raises it, opening the valve H and at the same time raises the arm h', thus permitting the spring g² to close the valve G'. The air from the chamber G, and consequently from the chamber a, immediately escapes to the atmosphere, and the pressure forces the valves D open, with the operation heretofore described. The pressure at which the relief device will act can be regulated by changing the tension of the spring M or the position of the weight N'. As soon as the receiver-pressure becomes reduced to the desired minimum the spring M and weight N', operating on the plunger K, close the valve k. The air in the chamber I' and cylinder I exhausts through the minute opening i². The springs H³ then force the valve H to its seat and at the same time, operating through the arm h', open the valve G', and the pumping action proceeds.

In this scheme of relief device the air in the compressor is of course reduced below that of the receiver-pressure, and it becomes necessary, therefore, to provide some valve device for preventing a backflow of fluid from the receiver. The check-valve F is provided for this purpose. An ordinary check-valve in this position hammers with each pulsation of the compressor. As it is desirable to prevent this action, I provide the following mechanism for this purpose: The check-valve is fixed on a stem f, which passes through the gland f' on the side of the valve-chamber E. Arranged on the stem f is an arm Q. A cylinder O extends from one of the passages d'. A plunger P is arranged in this cylinder and is connected with the arm Q by the connecting-rod p. The pin p', by

which the connection is made between the plunger and connecting-rod, is extended to each side of the plunger. Lugs o extend from the cylinder O, and the springs R R are tensioned between the pin p' and the lug o. These springs operating through the connecting-rod and arm Q close the valve F as soon as the plunger is relieved of air-pressure. As the cylinder O is connected with one of the pipes d', this takes place whenever the relief operation takes place, so that immediately the relief device is brought into operation the valve F is instantly closed through the action of the springs R R, thus preventing any escape of fluid from the receiver. As soon as the relief device is thrown out of operation, as heretofore described, and pressure is exerted on the fluid in the pipe d', pressure is exerted on the plunger P, and this is of sufficient area to overcome the springs R R, and thus open the valve F. By this mechanism the hammering of the valve F is prevented. It forms an instant check against the back movement of fluid from the receiver and is instantly opened when the pressure in the passages between the valve F and the compressor reaches a pressure approximating receiver-pressure.

It will be noted that the plunger K forms a primary motor and that this controls the valve controlling the secondary motor and that the counter-pressure on the primary motor may be adjusted by the tension of the springs M and the weight N', that the plunger H' forms a secondary motor controlling the relief device or valve, that the plunger P forms a motor by which the check-valve F is controlled. When the term "receiver" is used in the claims, it is intended to include any passage or receptacle into which fluid is pumped.

In the alternative construction shown in Figs. 6 and 7 the mechanism differs from that of the preferred construction in that the air is exhausted to the atmosphere with each operation of the compressor instead of being pumped from end to end and the valves D D operate with each reciprocation of the piston. In this construction the parts differing from those of the preferred construction are the cylinder I², which is connected with the passage I' and has in it a piston II⁶, which operates a valve-stem H⁴. This stem extends through the fitting i⁶, the fitting making a tight joint between it and the passage G³, leading to the receiver. An opening G² leads from the passage G³ to the atmosphere, and this is controlled by the valve at the end of the stem H⁴. A stem h⁶ extends from the piston above the cylinder. A yoke h⁴ is attached to this stem. A lock-nut h⁵ is provided for locking it in adjustment. The springs H³ are secured to the yoke. In the operation of this mechanism when the pressure exceeds the desired maximum the pis-

ton H^5 is forced upwardly, opening the valve at the end of the stem H^4 , and this immediately makes a relief-passage to the atmosphere. Inasmuch as the pipes d' are connected to the passage G^3 , the cylinders a are relieved of pressure, so that only the springs d hold the valve in a closed position. As the compressor continues the air is pumped past the valves D D and escapes by the passage G^3 .

What I claim as new is—

1. In a relief device for compressors the combination with the compressor-valve; a chamber for said valve; a primary motor; a valve controlled by said primary motor; means for connecting said primary motor with the passage into which fluid is pumped; a secondary motor controlled by the valve actuated by the primary motor; a fluid-passage into which the fluid is pumped by the compressor; a connection between said passage and said compressor-valve chamber; the valve G' in said connection; means for connecting the valve G' with the secondary motor; and the valve H controlling an outlet to the atmosphere from the connection between said passage and the valve-chamber whereby the connection is closed to the fluid-passage when said connection is open to the atmosphere.

2. In a relief device for compressors the combination with the compressor-valve D ; the chamber a in which said valve operates the passage E into which fluid is pumped by the compressor; a connection between said passage and the chamber a ; a primary motor connected with the passage into which fluid is pumped; a valve controlled by said motor, said valve controlling a passage leading to a chamber I' , said chamber having a contracted outlet-passage i^3 ; a secondary motor in communication with the chamber I' ; and valves operated by said secondary motor to close the connection between the passage E and the chamber a and to open the connection to bring the chamber a into communication with the atmosphere.

3. In a relief device for compressors the combination with the compressor-valve D ;

the chamber a in which said valve operates; the passage E into which fluid is pumped by the compressor; a connection between said passage and the chamber a ; a primary motor connected with the passage into which fluid is pumped; a valve controlled by said motor, 55 said valve controlling a passage leading to a chamber I' , said chamber having a contracted outlet-passage i^3 ; the secondary motor comprising the cylinder I and piston H' , the gland i on said cylinder; the valve H extending through said gland and connected with the piston H' ; the stem h extending from the piston H' ; the valve G' arranged to control the connection between the passage E and chamber a ; and means connecting the valve 60 with the stem h .

4. In a relief device for compressors a receiver connection in communication with the compressor; a valve arranged to prevent back-flow from said receiver connection toward the compressor; a valve-motor for opening said valve; a valve for controlling said valve-motor; a separate motor for actuating the relief device; and means acting with the relief device for actuating the valve controlling 75 the valve-motor.

5. In a relief device for compressors, the combination of the receiver connection E' ; the check-valve F for preventing a backflow of pressure therefrom; the stem f for said check-valve; the arm Q on said stem said stem and arm being arranged to actuate the valve F ; the cylinder O ; a plunger in said cylinder; springs tensioned against said plunger; a connection between said plunger and the arm on the stem; a passage controlled by the relief device for admitting fluid under pressure to said cylinder when the relief device is out of operation; means for reducing the pressure in said passage when the relief device is in operation and a separate motor for controlling the relief device.

In testimony whereof I affix my signature in presence of two witnesses.

RUDOLPH CONRADER.
